(57) **CLAIM**

The ornamental design for an image display apparatus, as shown and described.

DESCRIPTION

FIG. 1 is a front perspective view of an image display apparatus in accordance with our new design in which a display screen is shown as a flat display surface;

FIG. 2 is a front elevation view thereof;

FIG. 3 is a back elevation view thereof;

FIG. 4 is a top plan view thereof;

FIG. 5 is a bottom plan view thereof;

FIG. 6 is a right side elevation view thereof; and,

FIG. 7 is a left side elevation view thereof.
